EVAPORATIVE COOLER

Everett H. Osburn and Richard Walklin,
Phoenix, Ariz.

Application February 27, 1950, Serial No. 146,482

3 Claims. (Cl. 261—92)

1

This invention pertains to evaporative air coolers.

Heretofore some efforts have been made to conserve water used in evaporative coolers by means of pumps which re-circulate the water from a sump positioned below the evaporative pads, and apply to the top of the pads, and in other instances by cylindrical pads which rotate so that the lower portion of the pad dips into and travels through the water in the sump.

These coolers have the disadvantage that unless new water is continuously added to the sump and continuously drained off through an overflow the salt and alkali in the water in the sump becomes concentrated and tends to deposit on the pad thereby lessening its efficiency. Further, if the cylindrical pad is allowed to remain idle, with a portion of its periphery immersed in the sump-water, this wetted portion becomes heavier than the drier portion and unbalances the pad so that considerable power is needed to start the rotation of the pad. This puts an undue and excessive strain on the driving mechanism.

In view of the foregoing, one of the objects of our invention is to provide an evaporative cooler with an improved rotating pad member having more surface than the conventional cylindrical pads heretofore used;

A second object is to provide the cooler with means to automatically drain the sump at predetermined intervals so that when the pad is inoperative for any length of time it will completely dry out and there will be no damp area to cause unbalance;

A third object is to provide a mechanism for rotating the pad which is independent of the mechanism driving the blower;

A fourth object is to provide mechanism whereby fresh water entering the sump will assist in rotating the pad, and

A fifth object is to provide an improved means of constructing the casing so that the interior will be more accessible for adjustment and servicing of the mechanism.

Other objects will appear hereinafter.

I attain the foregoing objects by means of the mechanism and devices illustrated in the accompanying drawings in which:

Figure 1 is a side elevation of the cooler;

Figure 2, an end elevation thereof;

Figure 3, a vertical side section taken substantially on line 3—3, of Figure 4;

Figure 4, a plan view of the case with the top sectioned off to show the interior;

Figure 5 is a fragmentary portion of one end of the rotary pad support;

Figure 6 is a fragmentary sectional view of the pad structure; and

Figure 7, an electrical wiring diagram of the operating controls.

2

Similar numerals refer to similar parts in the several views.

The cooler housing or case 2 is composed of two main parts, a base 3 which is also a tank, and a cover 4 which encloses the working parts. Preferably the left or outer end 5 of the cover, the top 6, and the right end 7 can be made of one piece of sheet metal. The end uprights 8 and the intermediate upright 9 can be formed from the same piece of material, or they can be welded to the top piece to become integral therewith.

Blower vent 12 protrudes from the inner end 11. Side panels 14 are removable to give access to the blower, and outer side panels 16 are removable to give access to the rotating pad and its attendant mechanism. Circular air-inlet openings 17 are made in each of the panels 16 and collars 19 extend inwardly from the edges of these openings. The lower edges of cover 4, and the top edges of base 3 are folded inwardly at 18 and 20 respectively, to form a means of attachment, and these mating flanges are fastened together by screws 21.

Rotary evaporating element 24 is composed of two end disks 26 provided with central air-inlet holes 27 from the edges of which collars 28 extend outward. These disks are held together in correct relation to form a quasi-spool structure by rods 35 and 37 equally spaced and alternately arranged in two concentric annular circles. An evaporating pad 31 composed of an inner layer of excelsior 32 or other fibrous substance, held between coarse fabric 33 and 34, is threaded between these rods so as to pass over outer rods 35 and under inner rods 37.

A shaft 40 is held in the rotary element 24 by suitable spiders 41 within the holes 27 and is journaled at each end in bearing spiders 42 which are within collars 19 formed in case panels 16. Collars 19 fit within rotor collars 28 in order to form an air seal between the rotor and the case.

A shelf 43 is removably attached to one of the panels 16. This supports a motor 44 and reduction gear 49 so that shaft 40 can be driven at a slow speed.

At the inner end of the case a blower 45 is supported in base tank 3 by members 46. It is driven by motor 47 and air is directed out of case 2 through vent 12.

Water enters tank 3 through pipe 48, and is controlled manually by valve 50. Within the tank a float valve 51 maintains water at a level 52 so that the evaporative pad 31 will dip into and beneath the surface of the water. As the water enters it is directed downward and tangentially by nozzle holes on the lower side of pipe 53 so that it impinges on the surface of pad 31 at a position to the right of or eccentrically to its axis, as viewed in Figure 3, so as to produce clock-

wise rotation of the evaporating element 24. This assists motor 44 in turning the element and therefore this motor can be made quite small.

A drain 55 in the bottom of tank 3 is closed by a solenoid operated valve 56. The closing plug 57 of this valve is normally held up in open position by spring 58, and is forced to closed position by magnetic solenoid 59. The windings of this coil are connected in shunt with motor 44, as shown in Figure 7.

An overflow pipe 61 is also set into the bottom of base tank 3 to keep water therein at level 52, so that if float valve 51 fails to close water will not rise over the predetermined level.

The cooler is installed by positioning it adjacent the wall of an habitation to be cooled. Blower vent is connected to a duct leading to the rooms to be cooled, water pipe 48 is connected to a source of water under pressure, the two drains are connected to disposal lines and motors 47 and 44 connected to a source of electricity through line leads 62 and controlled by switches 63 and 64, respectively. When valve 50 is opened water is sprayed on the pad 31 and it is rotated as above explained. At the same time the blower can be started and operated to force air from vent 12 into any cooling ducts desired. Cooling starts almost immediately.

Air is drawn into the interior of case 2 through holes 27 and thence through pad 31 which is wetted by spray from pipe 53. This cooled air is then forced out vent 12 by blower 45. When motor 44 is started solenoid valve 56 closes. Water sprayed on pad 31 and not evaporated is accumulated in base tank 3 until level 52 is reached. Valve 51 then closes and pad 31 is maintained wet by running through this water in the tank. When the cooler is turned off, for any reason, drain valve 56 opens and drains all water from tank 3. This prevents the water from becoming stagnant and forming algae growths which cause the pad to give off unpleasant odors. The pad dries out completely and does not deteriorate rapidly.

Since the pad is folded in and out over bars 35 and 37 more evaporating surface is made available than if a plain cylindrical pad is used. Since there is more pad area the velocity of air passing through the pad can be reduced in order to attain better cooling.

This lower air velocity also prevents the drawing of water through the pad or off its surface in the form of small droplets, and eliminates the fault, common to this type of cooler, of blowing unevaporated water particles into the room to be cooled. On the other hand a pad, such as shown here, will become very unbalanced if it is allowed to stand for any length of time with its lower part immersed while its upper portion dries out. By the arrangement shown the entire pad dries out evenly when motor 44 is shut off. However the cooler can be reoperated immediately, when desired, because the entering water sprays on and wets the pad until tank 3 is filled. When starting, valve 50 is opened and when closing down this valve is closed. Obviously, valve 50 can be electrically operated when remote control is desired, and this can be done by a circuit in parallel with either motor, or by an independent circuit.

Since pad 31 should be cleaned or renewed from time to time and the other mechanism serviced, panels 14 and 16 are made removable independently of the case cover 4. The exact structure of the case may vary, however, with

the type of installation. Other parts of the device are, also, subject to wide variation and therefore we wish to be limited only to the following claims.

5 We claim:

1. An evaporative cooler, comprising in combination, a rectangular case having laterally positioned inlet openings; a rectangular tank in the bottom of said case, adapted to hold water up to a predetermined level; a blower at one end of said case adapted to draw air thereinto through said inlet openings and force it out through a vent in one of the walls of said case; a generally cylindrical rotary evaporating element operating at the other end of said case, having open ends connecting its interior to said inlet openings, and a peripherally disposed evaporative pad adapted to admit air into said case through said pad; means for wetting said pad and supplying water to said tank including a supply pipe connected to a source of water under pressure having outlet jets positioned to direct a spray of water tangentially against the outer surface of said rotary evaporating element; means for maintaining a pool of water in said tank at a level sufficient to immerse the lower portion of said pad; motor means adapted to rotate said evaporating element; and an electrically controlled valve in the bottom of said tank adapted to automatically open and drain said tank when said motor means is inoperative, and to close when said motor means is operating.

2. In an evaporative cooler having a case, a tank formed in the bottom of said case adapted to hold water at a predetermined level, an electrically driven blower for drawing air into said case and for forcing it therefrom, a rotary evaporative element rotated by an electric motor operative in said case so as to dip the lower circumferential portion thereof beneath the surface of the water in said tank, the combination therewith of means for drying out said pad by removing all water from said tank when said cooler is not in use, and for wetting said pad when starting operation, comprising an automatically operating drain valve having a closing plug normally held open by a spring, and closed by a solenoid electrically connected with said electric motor, adapted to rotate said evaporative element, so as to be energized only when said motor is operating, and a water supply pipe, connected to a source of water under pressure, provided with a constant level valve for maintaining water at a predetermined level in said tank, connected to spray discharge openings adapted to forcefully direct spray jets upon the circumferential surface of said evaporative element tangentially so as to aid rotation thereof by said motor and coincidentally wet the surface of said evaporative element during the course of a single revolution thereof.

3. In an evaporative cooler having a case with a sump at the bottom thereof, means for maintaining water therein at a predetermined level by water from a supply pipe controlled by a float valve, a blower therein adapted to draw air thereinto and discharge it through a vent into space to be cooled, and an electrically driven rotary evaporative element having a peripheral pad operative within said case having its circumferential periphery disposed to dip below the surface of water in said sump, the combination therewith of means for automatically drying said pad by removal of water from said sump, including a drain valve, normally held open by spring

means, and adapted to be closed by electrical means connected with the electrical means driving said rotary evaporative element, and means connected with the water supply float valve for directing a spray on the outer surface of said peripheral pad of said evaporative element when water is admitted through said float valve.
